UNITED STATES PATENT OFFICE.

JOSEPH F. HINDES, OF RELAY, MARYLAND, ASSIGNOR TO EMERSON DRUG COMPANY,
OF BALTIMORE, MARYLAND, A CORPORATION OF MARYLAND.

DESIGN FOR A COMMERCIAL VEHICLE FLOAT.

Application filed May 2, 1923. Serial No. 6,040. Term of patent 14 years.

To all whom it may concern:

Be it known that I, JOSEPH F. HINDES, a citizen of the United States of America, and resident of Relay, county of Baltimore, State of Maryland, have invented a certain new, original, and ornamental Design for Commercial Vehicle Float, of which the following is a specification.

In the accompanying drawing I have illustrated a commercial vehicle float embodying the features of my invention.

Figure 1 is a side elevation of the commer-

cial vehicle float, the mechanical parts not involved in the design being shown in broken lines.

Figure 2 is an elevation of the same looking from the right in Figure 1, which is the rear of the vehicle.

I claim—

The ornamental design for a commercial vehicle float substantially as shown.

Signed by me at Baltimore, Maryland,
this 1st day of May, 1923.

JOSEPH F. HINDES.
